JET AIRCRAFT SIMULATING TOY

Eddie A. Kreienbrink, 23206 U.S. 20, South Bend, Ind.

Filed Nov. 6, 1959, Ser. No. 58,246

Term of patent 3½ years

(Cl. D34—15)

Fig. 1

Fig. 2

Fig. 3

Fig. 4

Fig. 5

Fig. 1 is a top plan view of a jet aircraft simulating toy showing my new design with shoulder straps omitted for convenience of illustration;

Fig. 2 is a side elevational view thereof;

Fig. 3 is a front elevational view thereof;

Fig. 4 is a rear elevational view thereof with shoulder straps omitted; and

Fig. 5 is a reduced bottom plan thereof.

I claim:

The ornamental design for jet aircraft simulating toy, as shown.
